UNITED STATES PATENT OFFICE.

FREDERICK KAEMMER, OF MERIDEN, CONNECTICUT, ASSIGNOR TO THE STANLEY WORKS, OF NEW BRITAIN, CONNECTICUT.

DESIGN FOR A HINGE.

SPECIFICATION forming part of Design No. 25,356, dated April 7, 1896.

Application filed March 5, 1896. Serial No. 582,005. Term of patent 14 years.

To all whom it may concern:

Be it known that I, FREDERICK KAEMMER, a citizen of the United States, residing at Meriden, in the county of New Haven and State of Connecticut, have invented and produced a new and original Design for a Hinge, of which the following is a specification, reference being had to the accompanying drawing, in which the only figure is a face view of a hinge showing my design.

The contour of my hinge, when opened, is rectangular, and the ornaments are upon the face at diagonally-opposite corners.

The leaves $\Delta\Delta$ are of the ordinary rectangular form with any ordinary form of knuckles, and I have indicated in broken lines tips aa ; but said tips form no part of my design, and any other tips may be substituted therefor, or they may be omitted altogether.

The two diagonally-opposite corners have

upon their face the ornaments bb , extending from near the outer edge of each leaf inwardly toward the companion leaf for about half the width of each leaf and along near the outer edge of each leaf for a little more than half of the length or height thereof, as shown, while the rest of the surface is a plain or open field. The ornaments also surround the corner screw-holes cc on the corners to which said ornaments are applied. The said ornaments bb , as shown, consist mainly of combined flowerets, leaflets, and intertwining branches of curved form.

What I claim is—

The design for a hinge substantially as shown and described.

FREDERICK KAEMMER.
